UNITED STATES PATENT OFFICE.

DAVID E. SHAW, OF MILWAUKEE, WISCONSIN.

BOTTLE-WASHING MACHINE.

No. 867,310.

Specification of Letters Patent.

Patented Oct. 1, 1907.

Application filed August 4, 1906. Serial No. 329,154.

To all whom it may concern:

Be it known that I, DAVID E. SHAW, residing in Milwaukee, in the county of Milwaukee and State of Wisconsin, have invented new and useful Improvements in 5 Bottle-Washing Machines, of which the following is a description, reference being had to the accompanying drawings, which are a part of this specification.

This invention has for its object to provide a machine for thoroughly cleaning bottles on the interior and the 10 exterior, the bottles being placed on guides and forced upon rotary brushes into a locking position where they receive an injection of cleaning liquid with which the rotating brush cleans the interior and being turned by the frictional contact of the rotating brush to clean the 15 exterior by bearing against the guides in a cleaning solution.

The invention has for an object to provide a novel means for driving a series of rotating brushes from a common source of energy by belting them together by 20 a belt which crosses between the pulleys of the successive brushes.

Another object of this invention is to provide for automatically starting the injection of cleaning liquid into the bottle as the bottle is forced onto the rotary brush 25 and for automatically stopping the flow of cleaning liquid when the bottle is removed from the brush, the bottle being adapted to be locked on the brush in a position to continue the injection of cleaning liquid and serving to discharge the same into a separate receptacle 30 from that in which the bottle body remains.

With the above and other objects in view the invention consists in the bottle washing machine herein claimed, its parts and combinations of parts and all equivalents.

35 Referring to the accompanying drawings in which like characters of reference indicate the same parts in the several views; Figure 1 is a plan view of a bottle washing machine constructed in accordance with this invention; Fig. 2 is a sectional elevation thereof taken on the 40 plane of line 2—2 of Fig. 1; Fig. 3 is a transverse sectional view thereof taken on the plane of line 3—3 of Fig. 1; and, Fig. 4 is a central sectional view of one of the tubular spindles with its rotary brush.

In these drawings 6 represents a pair of tanks which 45 may be separate as shown or otherwise. A feed pipe 7 extends between the tanks and is rigidly supported in place in any suitable manner with a counter shaft 8 journaled thereon. The counter shaft is provided with a belt pulley 9 to be belted with any suitable driving 50 mechanism and a grooved pulley 10 for driving a series of rotary brushes. The feed pipe 7 connects with any suitable source of supply of cleaning liquid under pressure, preferably with the water mains, and at intervals 55 has T-connections 11 connected by couplings 12 with T-connections 13 which form journal bearings for tubu-

lar spindles 14 carrying grooved pulleys 15. A belt 16 passes around the grooved pulley 10 on the counter shaft and around each of the grooved pulleys 15 on the tubular spindles crossing itself between each pair of pulleys and passing around a grooved pulley 17 at the 60 end of the series which is carried by a frame 18 slidably mounted on the feed pipe 7 so as to move toward or away from the series of pulleys 15. This pulley 17 forms a belt tighten and is given a tendency to move in the direction to keep the belt 16 tight by being connected with a weight 19 suspended therefrom by a cord 20 passing over a pulley 21 on the end of the feed pipe 7.

The T-connection 13 for each tubular spindle 14 is more than a mere journal bearing therefor as it serves to establish communication between the interior of the 70 tubular spindle and the supply pipe 7, the tubular spindle being provided with perforations 22 which come into register with the opening leading from the supply pipe and the ends of the bearing being protected by right and left hand packing glands 24 to prevent the escape of liquid therefrom. The pulley 15 by abutting against a packing gland 23 on one side of the bearing prevents a longitudinal movement of the tubular spindle in one direction and a set collar 24 on the tubular spindle prevents a longitudinal movement 80 in the other direction by abutting against the other packing gland.

The ends of the tubular spindles 14 are reduced in internal diameter to form shoulders or valve seats 25 and a tubular stem 26 fits in each of these reduced end 85 portions with an enlarged head at its end forming a valve 26', there being openings 27 in the stem a short distance from the valve to establish communication between the tubular spindle and the stem when the stem is forced inwardly to move the valve 26' from the 90 valve seat 25. The inward movement of the stem is limited by a set pin 28 thereon riding in a longitudinal slot 29 of the tubular spindle, this arrangement also serving to cause the stem 26 to rotate with the tubular spindle. The tubular spindle has tufts to constitute 95 a rotary brush 30 and at the forward end there are inclined openings 31 in the stem 26 to discharge cleaning liquid into the bottoms of the bottles when they are placed on the brush and forced against the end of the stem so as to open the valve 26'.

100 The tanks 6 are divided by partitions 32 near one edge thereof, the main portion of the tank being intended to contain a strong alkaline solution and the narrow space between the partition and the edge of the tank next thereto being adapted to discharge through 105 spouts 33. Within the main portion of the tanks and beneath each rotary brush there is a V-shaped guide 34 which is preferably connected with partitions 32.

In operation the motion of the counter shaft 8 is imparted to each of the tubular spindles 14 by the belting 110

connection 16 to cause the rotation of the rotary brushes 30. These brushes dipping into the alkaline cleaning solution in the main portion of the tanks take up some of the cleaning solution so that when a bottle is forced 5 along a guide 34 and onto one of the rotary brushes, the alkaline cleaning solution is carried into the bottle and the brush rotating therewith removes the foreign matter from the interior of the bottle, and as the bottle is pressed against the end of the brush stem to open the 10 valve 26' a supply of water or other cleaning or rinsing liquid is injected into the bottle through the openings 31. The engagement of the head of the bottle with a V-shaped notch 35 of the partition 32 serves to hold the bottle in the position where it will keep the valve open 15 and allow of the cleaning operation to continue while the operator proceeds to place another bottle on the next rotary brush in a like manner.

Besides the bottle becoming thoroughly cleansed on the interior, the friction of the brush therewith 20 causes it to turn in the guide, and the guide bearing against the outside of the bottle with the assistance of the alkaline solution in the tank removes the label and all other foreign matter so that the exterior of the bottle is also thoroughly cleaned.

25 While the liquid injected into the bottles is referred to as a cleaning liquid and may be a chemical preparation for more thoroughly removing foreign matter from the interior of the bottles than would be the case with water, it is obvious that hot or cold water or another 30 rinsing liquid may be employed with the function of rinsing the bottle after the cleaning liquid has been used therein by the rotary brushes.

When the brushes have all been supplied with bottles, the operator then begins to remove the bottles first 35 placed in position and replace them with other bottles to be cleaned, the number of rotary brushes provided for each operator being as many as are required to allow each bottle to remain in place the desired length of time.

40 With this apparatus the alkaline solution with which the bottles are washed on the interior and also on the exterior is not diluted by the rinsing liquid, for the water passes from the mouths of the bottles into the smaller compartment of the tank and is discharged 45 through the spouts 33.

What I claim as my invention is—

1. A bottle cleaning machine, comprising a tank containing cleaning liquid, a rotary brush dipping in the cleaning liquid and adapted to have a bottle placed thereon, means for injecting a liquid into the bottle when the 50 bottle is forced onto the brush and means for keeping the injected liquid separate from the liquid in the tank.

2. In a bottle washing machine, a tubular spindle connected with a liquid supply and having a valve seat, a 55 tubular stem slidably fitting in the tubular spindle and provided with a valve for engaging the valve seat, and a rotary brush on the stem adapted to receive a bottle and

be forced thereby to open the valve and permit the liquid to be injected into the bottle through the tubular stem.

3. In a bottle washing machine, a tubular spindle having connection with a liquid supply and provided with a valve seat, a tubular stem fitting in the spindle and having a valve on its end for normally closing the valve seat, a set pin on the tubular stem riding in a slot of the tubular spindle, and a rotary brush formed on the tubular stem 60 and adapted to receive a bottle, there being an inclined opening in the end of the tubular stem through which liquid may be injected into the bottle when the stem is moved by means of the bottle to open the valve.

4. A bottle washing machine, comprising a tank containing cleaning liquid, a rotary brush dipping into the cleaning liquid of the tank and adapted to receive a bottle thereon, means for injecting liquid into the bottle when it is in position on the brush, and means for receiving the liquid from the bottle mouth and carrying it away without mixing it with the liquid in the tank.

5. A bottle washing machine comprising a pair of tanks containing cleaning liquid, a liquid supply pipe, T-connections communicating with the liquid supply pipe and supported thereby, tubular spindles journaled in the T-connections, grooved pulleys carried by the tubular spindles, means in connection with the grooved pulleys for driving the tubular spindles, said tubular spindles having communication with the supply pipe through the T-connections, valved tubular stems in the ends of the spindles, 85 rotary brushes formed thereon, partitions in the tanks, and V-shaped guides on the partitions for engaging the outside of the bottles when they are placed on the rotary brushes, the tubular stems being adapted to inject liquid into the bottles when the bottles are pressed thereon, and the partitions being adapted to engage the heads of the bottles to hold them pressed against the tubular stems, the liquid passing from the mouths of the bottles and into the tanks on the other side of the partitions.

6. In a bottle washing machine, a tubular spindle having connection with a liquid supply and provided with a valve seat, a tubular stem fitting in the spindle and having a valve for normally closing the valve seat, a pin on the tubular stem riding in a slot of the tubular spindle, and a rotary brush formed on the tubular spindle and adapted to receive a bottle, there being an opening in the tubular stem through which liquid may be injected into the bottle when the stem is moved by means of the bottle to open the valve.

7. In a bottle washing machine, a grooved drive pulley fixed in its position, a grooved take up pulley adjustable with relation to the drive pulley, an intermediate grooved pulley, a belt connecting the several pulleys and crossing itself between the drive pulley and the intermediate pulley and between the intermediate pulley and the take up 110 pulley, a tubular spindle carried by the intermediate pulley, a water jacket surrounding the tubular spindle and communicating therewith, and a brush carried by the spindle and supplied with water therefrom, the said intermediate pulley being balanced by the opposing forces 115 thereon so as to require no fixed bearings and to relieve the water jacket from wear.

In testimony whereof, I affix my signature, in presence of two witnesses.

DAVID E. SHAW.
